UNITED STATES PATENT OFFICE

2,150,277

HEEL-SEAT FITTING MACHINE

George Hazelton, Leicester, England, assignor to
United Shoe Machinery Corporation, Paterson,
N. J., a corporation of New Jersey

Application May 11, 1938, Serial No. 207,217
In Great Britain May 29, 1937

8 Claims. (Cl. 12—31.5)

This invention relates to machines for use in the manufacture of shoes and is illustrated as embodied in an improved heel-seat fitting machine.

It is sometimes the practice in the manufacture of compo shoes having short outsoles which are made of leather, rubber or composition material, to cement, or otherwise adhesively secure, substantially the entire heel-seat portion of the sole to the shoe bottom during the sole-laying operation. It is an object of the present invention to improve machines of the general type disclosed in United States Letters Patent No. 1,850,149, granted March 26, 1932 on an application filed in my name, to adapt them for quickly and effectively reducing the heel-seat portions of soles of shoes such as above described for the reception of heels.

With the above object in view, and in accordance with a feature of the present invention, the illustrated machine is provided with crease plates which are forced against and stopped by an adhesive bond securing a sole to a compo shoe, means for trimming surplus material from the heel-seat portion of the sole which heel-seat portion is adhesively secured throughout substantially its entire extent to the bottom of the shoe, and means for breaking the adhesive bond securing the surplus material to the shoe bottom whereby to release the material from the shoe bottom.

During the operation of the illustrated machine a pair of knives which constitute the above-mentioned means for breaking the adhesive bond, move inward between the shoe bottom and the lateral margins of the cemented-down heel-seat portion of the sole sufficiently to release from the shoe bottom the surplus material which is trimmed from the opposite sides of the heel-seat portion of the sole by heel-seat reducing and shoulder-forming knives. The bond-breaking knives do not sever the bond between the formed heel-seat tab and the shoe bottom, thereby insuring that the tab shall serve as a firm foundation to which the heel may be effectively secured.

The various features of the invention will be understood and appreciated from the following detailed description read in connection with the accompanying drawings, in which

Fig. 1 is a plan view, partly broken away, of a portion of the illustrated heel-seat fitting machine;

Fig. 2 is a vertical section, partly broken away, on line II—II of Fig. 1;

Fig. 3 is an angular view showing operative por-

tions of the illustrated machine in the process of reducing the cemented-down heel-seat portion of the sole of a shoe;

Fig. 4 shows a portion of the machine, partly broken away, and a shoe being operated upon, in section on line IV—IV of Fig. 1;

Figs. 5, 6 and 7 are sections on line V—V of Fig. 3 during three different stages of the heel-seat fitting operation; and

Fig. 8 is an angular view of the heel end of a 10 shoe the heel-seat portion of which has been reduced by the above machine, the original heel-seat portion of the sole and a heel of the shoe being shown in dash lines.

The illustrated machine is described with reference to reducing the heel-seat portions 20 (Figs. 3 and 8) of short outsoles 22 of compo shoes 24, which heel-seat portions are adhesively secured throughout substantially their entire extent to the shoe bottoms 26, for the reception of heels. 20 The shoe 24, which is off the last, is mounted on a jack 30 (Figs. 1 and 4) slideable along a guideway 31 (Fig. 1) in the machine frame. The shoe 24 on the jack 30 is then moved rearward causing a pair of crease plates 32 to register between the 25 laterally projecting margins of the sole 22 and the overlasted counter portion of the shoe, rearward movement of the sole being limited by a back gage 36 (Fig. 2) which is engaged by the rear end of the shoe.

A treadle (not shown) is then depressed to move the crease plates 32 toward each other until they are forced against the adhesive bond 38 (Figs. 4 and 5) by which the sole is secured to the shoe bottom 26, thereby locating the shoe widthwise and heightwise in the machine. Upon continued depression of the treadle the jack 30 is raised slightly causing the bottom 26 of the shoe to be forced against the undersides of the crease plates 32 and the central part of the heel-seat portion 20 of the sole 22 to be forced against a holdown 40.

After the shoe has been positioned and clamped in the machine as above described, knives 42 which are secured to carriers 44 by screws 46 are moved inward from opposite sides of the shoe to form heel-breast receiving shoulders 48 (Fig. 8) on the sole. A pair of beveling knives 50 having cutting edges 52 inclined to the general plane of 50 the sole are then moved forward to reduce the heel-seat portion of the sole thereby cooperating with the shoulder-forming knives to provide a heel-seat tab 54 (Fig. 8). Since the inward movement of the crease plates 32 is stopped by 55

the adhesive bond 38 securing the sole to the bottom 26 of the shoe, it is desirable that the paths of movement 56 (Fig. 3) of the lower ends 58 of the cutting edges 52 of the beveling knives 50 be spaced inward from the crease plates 32 thereby providing a heel-seat tab which is narrow enough to insure the proper seating of the heel upon the shoe.

When the entire heel-seat portion 20 of the sole 22 is cemented to the shoe bottom 26, the surplus material 60 (Figs. 7 and 8) which is severed from the heel-seat portion of the sole by the shoulder-forming and the beveling knives 42, 50, respectively, has to be released from the shoe bottom.

In order to release the surplus material trimmed from the heel-seat portion 20 of the sole from the bottom of the shoe, each of the carriers 44 has secured to it by screws 62 (Figs. 1, 3 and 4) a bond-breaking knife 64 (Figs. 2, 3 and 4) having a straight cutting edge 66 (Fig. 3) extending lengthwise of the shoe and lying approximately in the plane of the upper face 68 of the corresponding crease plate 32. The cutting edges 70 of the shoulder-forming knives 42 approximately meet the cutting edges 66 of the bond-breaking knives 64, the arrangement being such that the bond-breaking knives during their inward travel toward each other, break the adhesive bond between the lateral margins of the heel-seat portion 30 of the sole and the shoe bottom. The bond-breaking knives 64 move inward until their cutting edges 66 intersect the paths of movement 56 of the lower ends 58 of the cutting edges of the heel-seat reducing or beveling knives 50, thereby separating the adherent surplus material trimmed from the heel-seat portion of the sole from the shoe bottom.

The crease plates 32 are secured by screws 72 (Figs. 1, 2 and 3) to sliding beds 74 (Figs. 1, 2 and 4) which are movable along guides 76 (Fig. 2) of the machine frame. Secured by screws 77 to the sliding beds 74 are rods 78 (Figs. 1 and 2) pivoted to links 80 the lower ends of which are pivoted to a vertical slide 82 (Fig. 2) connected through suitable mechanism to the above-mentioned treadle (not shown). Upon depressing the treadle against the action of a spring 84 the vertical slide is lowered causing the sliding beds 74 to move inward toward the median plane 86 (Fig. 1) of the machine until the crease plates 32 are forced against the cement bond 38 (Figs. 4 and 5) between the sole and the shoe bottom. The crease plates 32 (Fig. 3) extend forward of the heel-breast line 88 (Figs. 3 and 8) of the sole 55 and are provided with surfaces 90 (Fig. 3) over which the shoulder-forming knives 42 travel. It will be noted that the inner edges of the crease plates 32 are rather blunt and may be forced with considerable pressure against the adhesive bond between the sole and the shoe bottom without splitting the bond.

After the shoe, positioned lengthwise by the back gage 36, (Fig. 2) has been clamped between the crease plates 32, the operator continues to depress the treadle (not shown) causing the jack 30 to be raised, thereby forcing the shoe bottom against the under sides of the crease plates and the central part of the heel-seat portion 20 of the sole against the holdown 40. The holdown 40 is threaded into a bracket 94 (Figs. 1 and 2) secured by screws 96 to the main frame and may be adjusted into different heightwise positions with relation to the bracket. The mechanism for operating the crease plates 32 and the jack 30 is identical with corresponding mechanism of the

heel-seat fitting machine disclosed in United States Letters Patent No. 1,847,244, granted March 1, 1932 on an application filed in the names of Hazelton and Ricks, upon which the above-mentioned Letters Patent No. 1,850,149 is an improvement. Accordingly it will be unnecessary further to describe the above mechanism herein.

The back gage 36 (Fig. 2) is moved into different operative positions in accordance with the length of the heel 28 in a heel gage 98 (Figs. 1 and 2) through mechanism which is fully described in both of the above-identified Letters Patent which may be referred to for a further understanding of the construction and operation of the machine.

The carriers 44 to which the shoulder-forming and the bond-breaking knives 42, 64, respectively, are clamped, are secured by screws 100 (Figs. 1, 2 and 4) to slides 102 movable along guides 104. Screws 106 (Figs. 1 and 4) which are threaded into the slides 102 and are secured to the slides by nuts 107, pass through elongated slots 108 (Figs. 1 and 4) in the guides 104. The lower ends of the screws 106 carry anti-friction rolls 110 fitting in arcuate channels 112 of plates 114 formed integral with blocks 116 (Fig. 1) which are movable along guideways 118 of the respective sliding beds 74 (Figs. 1, 2 and 4). The blocks 116 are moved along the respective guideways 118 by offset bell-crank levers 120 (Figs. 1 and 2) which are pivoted upon the depending rods 78 carried by the sliding beds 74 and have bifurcated forward ends (Fig. 1) for receiving depending pins 122 (Figs. 1 and 2) secure to the blocks 116. The offset bell-crank levers 120 are rotated upon the depending rods 78 by elongated links 124 (Fig. 2) the rear ends of which are pivoted to a slide 126 which is movable along a guideway 128 and has secured to it a roll 130 fitting in a groove 132 of a rotary cam 134.

The guides 104 (Figs. 1, 2 and 4) may be adjusted into different angular positions upon the respective sliding beds 74 to vary the paths of movement of the shoulder-forming knives 42 and the bond-breaking knives 64 transversely of the sole through the following mechanism. Passing through a recess in each of the guides 104 is a threaded shank 135 of a clamp 136 which may be forced against the under sides of the corresponding sliding bed 74 through the provision of a nut 140 which is threaded on the shank. Threaded into the inner ends of each of the guides 104 is a screw 142 (Figs. 1 and 4) which passes through an arcuate slot 144 in a corresponding sliding bed 74. The slots 144 and the outer faces 146 of the sliding beds are centered about vertical axes passing through points 145 which are located at the forward limits of movement of the lower ends 58 (Fig. 3) of the cutting edges 52 of the beveling knives 50. When the nuts 140 and the screws 142 have been loosened the guides 144 are swung about the respective axes 145 until they are in the desired angular positions conveniently determined by graduations 148 (Fig. 1) on the sliding beds 74. The nuts 140 and the screws 142 are then tightened to clamp the guides 104 securely to their sliding beds 74.

With the above arrangement it will be clear that as the sliding beds 74 move inward to force the crease plates 32 against the adhesive bond 38 (Figs. 4 and 5) securing the sole 22 to the shoe bottom 26 they carry with them the guides 104 and the slides 102 through which the shoulder-forming knives 42 and the bond-breaking knives 64 are operated. The arrangement of the bell-

crank levers 120 and the links 124 is such that there is practically no relative movement between the slides 102 and their respective sliding beds 74 during the movement of the beds.

5 After the shoe has been positioned in the machine a one-revolution clutch (not shown) is tripped causing the cam 134 to rotate and through the above mechanism to operate the shoulder-forming knives 42 and the bond-breaking knives 10 64.

10 The heel-seat reducing knives are secured by screws 150 (Figs. 2, 3 and 4) to carriers 152 which are movable forward and rearward along guideways 154 (Fig. 4) of raised overhanging portions 15 156 of the sliding beds 74. The rear ends of the carriers 152 are provided with grooves 158 (Figs. 1 and 2) for receiving a transverse bar 160 of an operating slide 162 (Fig. 2) which is movable along a guideway (not shown) in the machine 20 frame and has secured to it a depending roll 164 fitting in a groove 166 of the rotary cam 134.

25 It has been found preferable to form the heel-breast receiving shoulders 48 and to break the adhesive bond 38 between the shoe bottom 26 and the lateral margins of the heel-seat portion of the sole before reducing the heel-seat portion and, accordingly, the shoulder-forming and the cement-breaking knives 42 are operated before the beveling knives. It will be appreciated, how- 30 ever, that the sequence of operation of the heel-seat reducing knives on the one hand and the shoulder-forming and the bond-breaking knives on the other hand may be reversed.

35 Having described the invention, what I claim as new and desire to secure by Letters Patent of the United States is:

40 1. A heel-seat fitting machine having, in combination, crease plates constructed and arranged to be forced against and stopped by an adhesive bond securing a sole to a compo shoe, means for trimming surplus material from the heel-seat portion of the sole which heel-seat portion is adhesively secured throughout substantially its entire extent to the bottom of the shoe, and means for breaking the adhesive bond securing said 45 surplus material to the shoe bottom in order to release said material from the shoe bottom.

45 2. A heel-seat fitting machine for operating upon a shoe the sole of which, including substantially its entire heel-seat portion, is secured by an adhesive bond to the bottom of the shoe having, in combination, crease plates constructed and arranged to be forced against and stopped by portions of the adhesive bond which are located forward of the heel-breast line of the shoe, means for trimming surplus material from the heel-seat portion of the sole to reduce the same for the reception of a heel, and knives for breaking the adhesive bond between said surplus material 50 and the shoe bottom whereby to release said surplus material from the shoe bottom.

55 3. A heel-seat fitting machine having, in combination, crease plates constructed and arranged to be interposed between the bottom of a compo shoe and the projecting lateral margins of the sole of the shoe which sole has substantially its entire heel-seat portion adhesively secured to said shoe bottom, means for trimming surplus material from said heel-seat portion of the sole to provide a heel-seat tab which is secured to the shoe bottom, and knives having cutting edges movable inward from opposite sides of the sole to break the adhesive bond between the bottom of the shoe and said surplus material whereby to release the material from the shoe bottom.

4. A heel-seat fitting machine having, in combination, a pair of crease plates, a pair of knives for reducing the heel-seat portion of the sole of a compo shoe which heel-seat portion is adhesively secured through substantially its entire extent to the bottom of the shoe, means for operating said heel-seat reducing knives, a pair of shoulder-forming knives which move inward from opposite sides of the shoe and cooperate with said heel-seat reducing knives to sever surplus material at opposite sides of said heel-seat portion from the sole, a pair of knives movable inward with the shoulder-forming knives for breaking the adhesive bond between said surplus material and the shoe bottom in order to release the material from the shoe bottom, and means for operating the shoulder-forming and the bond-breaking knives.

5 5. A heel-seat fitting machine having, in combination, crease plates constructed and arranged to be interposed between the bottom of a compo shoe and the projecting lateral margins of the sole of the shoe which sole has substantially its entire heel-seat portion adhesively secured to the shoe bottom, knives movable lengthwise of the sole to reduce the heel-seat portion of the same, knives which are movable inward from opposite sides of the sole to form heel-breast receiving shoulders on the sole and which cooperate with said heel-seat reducing knives to sever surplus material at the opposite sides of the heel-seat portion from the sole, means for operating the heel-seat reducing knives, knives having cutting edges arranged adjacent to the sole-engaging faces of the respective crease plates, said last-named knives being movable inward from opposite sides of the sole together with the shoulder-forming knives to break the adhesive bond between the shoe bottom and the surplus material of the heel-seat portion of the sole, and common means for operating the shoulder-forming and the bond-breaking knives.

20 6. A heel-seat fitting machine for operating upon a shoe the sole of which including substantially its entire heel-seat portion is secured by an adhesive bond to the bottom of the shoe having, in combination, crease plates, a pair of knives having cutting edges which are inclined to the heel-seat portion of the sole and are movable forward in paths spaced inward from the respective crease plates to reduce the heel-seat portion of the sole, knives for forming heel-breast receiving shoulders upon the sole, and knives for breaking the adhesive bond securing the surplus material of the heel-seat portion of the sole to the shoe bottom whereby to insure that said material shall be released from the shoe bottom.

25 7. A heel-seat fitting machine having, in combination, a back gage for positioning lengthwise a shoe the sole of which, including substantially its entire heel-seat portion, is secured by an adhesive bond to the bottom of the shoe, crease plates constructed and arranged to be forced against and stopped by portions of the adhesive bond which are positioned immediately forward of the heel-breast line of the sole whereby to position said heel-seat portion of the sole heightwise and widthwise, a pair of knives having cutting edges which are inclined to the heel-seat portion of the sole and are movable forward in paths spaced inward from the respective crease plates to reduce the heel-seat portion of the sole, shoulder-forming knives movable widthwise of the sole and cooperating with the respective heel-seat reduc- 30

- ing knives to trim surplus material at opposite sides of the heel-seat portion from the sole, and knives having cutting edges constructed and arranged to break the adhesive bond between the lateral portions of the heel-seat portion of the sole and the shoe bottom to insure that surplus material trimmed from the sole by the heel-seat reducing and the shoulder-forming knives shall be released from the shoe bottom.
- 10 8. A heel-seat fitting machine for operating upon a shoe the sole of which, including its entire heel-seat portion, is secured by an adhesive bond to the bottom of the shoe having, in combination, knives which are movable lengthwise of the

sole to reduce the heel-seat portion thereof, a pair of knives for forming heel-breast receiving shoulders on the sole and for cooperating with the heel-seat reducing knives to trim surplus material at said heel-seat portion from the sole, bond-breaking knives which are movable inward from opposite sides of the sole between the margins of the heel-seat portion of the sole and the shoe bottom, and means for moving the cutting edges of the bond-breaking knives substantially to but not substantially beyond the paths of movement of the cutting edges of corresponding heel-seat reducing knives.

GEORGE HAZELTON.
